DOOR FRAME

Morris Rubin, North Bellmore, N.Y., assignor to North East Metal Products Corporation, Merrick, N.Y., a corporation of New York

Filed May 18, 1960, Ser. No. 60,631

Term of patent 14 years

(Cl. D13—1)

FIG. 3

FIG. 4

Fig. 1 is a side elevational view of a door frame showing my new design;

Fig. 2 is an elevational view showing the reverse side of the door frame;

Fig. 3 is a sectional view taken on the line 3—3 of Fig. 2; and

Fig. 4 is a sectional view taken on the line 4—4 of Fig. 2.

I claim:

The ornamental design for a door frame, as shown.
